READING MACHINE

Filed Nov. 22, 1930

UNITED STATES PATENT OFFICE

BRADLEY A. FISKE, OF NEW YORK, N. Y.

READING MACHINE

Application filed November 22, 1930. Serial No. 497,405.

My present invention relates to improvements in reading machines, and my object generally is to provide a machine for the purpose, simple in construction, of light weight, capable of being folded so as to occupy little space, and highly efficient and convenient in operation.

With the present machine, the printed matter is carried on sheets or strips of fairly stiff paper and arranged in horizontal and vertical columns. Good results have been obtained with sheets or strips having a length of about eight and one-half inches and a width of about two and one-half inches, each 10 panel of printed matter being approximately five-eights inch in its vertical dimension and one-half inch in its horizontal dimension. Of course it will be understood that the figures given are simply for illustration and 15 may be varied within substantial limits.

With my present improved machine, the paper strip is held frictionally in a simple form of carrier which is adjustable vertically to permit the successive horizontal rows or 20 panels of printed matter be brought into the field of view of the lens or glass. In operation after the printed matter on any particular panel has been read, the strip is shifted sideways so as to bring the succeeding panel 25 in the same horizontal row into view. This feeding of the paper strip may be effected in any suitable way but I have devised for the purpose an improved form of feeding means which I prefer to use and which will 30 be later described and incorporated in some of the appended claims.

My improved machine employs a lens or glass of suitable power properly mounted with respect to the printed matter and associated with means by which focussing can 40 be effected. The lens or glass is so mounted with respect to the main frame of the machine that when not in use it may be folded in close proximity to said frame so as to make 45 the device flat and compact. Means are also provided by which when out of use the handle may be telescoped vertically with respect to the main frame so as to secure compactness in a vertical direction.

50 In order that the invention may be better

understood attention is directed to the accompanying drawing, forming part of this specification and in which

Figure 1 is a side elevation showing the machine in use and illustrating in outline the 55 hand of the user.

Figure 2 is a section on the line 2—2 of Figure 1 looking in the direction of the arrows in the latter figure.

Figure 3 a rear elevation of the upper portion of the improved reading machine showing the uppermost position of the paper carrier in dotted lines.

Figure 4 a sectional view on the line 2—2 of Figure 2 looking in the direction of the 60 arrows on the latter figure, and

Figure 5 a detailed view of a suitable arrangement of paper strip carrying the printed matter. In all of the above views 70 corresponding parts are represented by the same characters.

Most of the parts of my improved reading machines are preferably made of duralumin in order to secure the necessary strength and stiffness with extreme lightness but other materials may of course be used.

The main frame 1 is flat and is formed at its upper end with the prongs 2—2 serving to guide and to assist in keeping the paper sheet flat in the paper carrier. Mounted upon the main frame 1 is a handle 3 the portion 4 thereof being preferably of wood and said handle is provided with overturned flanges 3' extending around the edges of the main frame 1 as shown, and engaging said frame 85 with sufficient friction as to be maintained in place when extended to the reading position shown in Figures 1 and 2. Obviously the handle 3 may be moved upwardly into a 90 telescoping position with respect to the main frame 1 owing to its frictional engagement therewith. A small pivoted latch 5 normally prevents the handle from being moved beyond the correct position for reading but by 95 lifting this latch and swinging it out of the way the handle may be removed as will be obvious.

The main frame is preferably cut away as at 6, to secure lightness, and bridging the 100 legs formed by the cutaway portion is a

spacer 7 to which is riveted or otherwise secured a vertical support 8 for the paper carrier.

The paper carrier fits into the space between the support 8 and the main frame and comprises a plate 9 having spaced paper clips 10 and 11 at the top and bottom, respectively. The plate 9 is provided with two guides 13—13 sliding upon the support 8 whereby the paper carrier will be firmly supported at all times and guided accurately in its vertical adjustments.

Bridging across the guides 13 is a bridge 14 which completes the mounting of the paper carrier and from this bridge and integral therewith extends a spring tongue 15 pressing upon the guide 8 with sufficient friction to hold the paper carrier in any position of adjustment. The glass or lens 16 is of any suitable power and is carried at the upper end of a lens support 17.

A bar 18, preferably circular in cross section, is pivoted between lugs 19—19 to the main frame, whereby the bar may be moved pivotally with respect to said frame. A tongue 20 is formed in the main frame and engages the flat inner end of the rod 18 with sufficient spring tension to hold said rod and the lens or glass steady in the reading position. At the same time the tongue 20 permits the rod 18 to be moved pivotally with respect to the main frame and it assures the parts snapping smartly into reading position as shown in Figure 1 when they are unfolded.

Embracing rod 18 is a sleeve 21 pivoted between lugs 22 on the lens support 17. A tongue is formed in this lens support similar to tongue 20 and engages the outer end of the sleeve 21 so as to maintain the lens support in its desired vertical position. Secured to the rod 18 is a small rack 23 working in a slot in the sleeve 21 so as to prevent a turning movement of the lens support with respect to the rod 18 as clearly shown in Figure 2. Sleeve 21 is of rectangular form on its exterior. The rack 23 is engaged by a small pinion (not shown) on the shaft 24 which is turned by a milled wheel 25 when focussing is to be effected.

The printed matter is preferably carried on a strip of fairly thick paper 26 sufficiently stiff to maintain itself properly in the paper carrier, and it may conveniently be of the dimensions heretofore given. The printed matter is in the form of panels, preferably sufficiently small as to be comprehended within the field of view of the lens, as in this way an entire panel or page can be read without making any adjustment of the paper. The panels or pages of printed matter are arranged in horizontal rows as shown in Figure 5, three of such rows being illustrated. They are separated a short distance and the panel of one row is preferably in vertical

line with the corresponding panel of the other row or rows.

In order to feed the paper held in the paper carrier horizontally to bring the panels or pages of printed matter successively into view, I prefer to employ the special feeding mechanism shown in the drawing. This comprises a shaft 27 vertically mounted with respect to the carrier 1. At its lower end the shaft 27 is mounted in a bearing 28 with a fairly close fit. Near its other end, the shaft 27 turns within a staple or eye 29 so that said shaft may move toward and away from the paper strip. Carried by the shaft 27 is a knurled wheel 30 and in line therewith is a cutaway portion 31 in the main frame permitting clearance of the knurled wheel when the same is pressed toward the frame as I will explain. Secured to the upper end of the shaft 27 is a feeding disk or wheel 32 made of some suitable elastic or yielding material. I prefer to employ for this purpose rubber of the quality used in the manufacture of so-called rubber heels as I find that this material works admirably. One of the legs 2 of the main frame is cut away as at 33 to give clearance to the wheel 32.

In operation when it is desired to feed the paper horizontally, the thumb of the user is pressed against the knurled wheel 30 causing the shaft 27 to spring slightly and thus engaging the feed wheel 32 with considerable pressure upon the paper strip. While thus being pressed down the knurled wheel 30 is rotated, thus moving the paper strip frictionally until the next panel comes into view. After all the pages or panels in one horizontal line have been read the strip is returned by hand or by reversing the movement of the feed wheel 32, whereupon the paper carrier is elevated sufficiently to bring the next row of panels into the field of view of the lens.

Although I have not illustrated it in the drawing, it will of course be understood that I may employ a blinder for cutting off the field of view of the idle eye, said blinder being pivoted to the ring or frame supporting the lens or glass, as I have described in patents heretofore granted to me.

When the printed matter on the paper strip is typographic and is to be read by the user it is preferably secured by photographically reducing to the desired extent type-written characters, but obviously the characters need not be typewritten, and the reduction can be obtained in other ways than by photography.

My improved reading machine, however, is not limited for use with typographic characters, photographically or otherwise reduced. The printed matter constituting the several panels on the strip may be very small and in a sense microscopic photographs or pictures of any desired kind, such for example, as photographs of machinery, people,

landscapes, etc. These photographs may be wholly unrelated to each other or there may be a relation between the photographs on the successive panels. For example, the successive photographs may represent the different members of the President's Cabinet or they may represent the same individual at different ages. Another example or related photographs would be the representation of say ten pictures of an engine taken at ten successive positions of a complete cycle of its operation placed side by side on a card or strip so that when moved sidewise one after the other an effective study of the complete operation can be secured in a very convenient way.

It is a curious fact that when very small, practically microscopic photographs are thus observed through a lens or glass as with my improved reading machine, the impression of depth and reality is much more vivid than with an ordinary sized photograph or picture printed on a flat piece of paper. This effect may be due to the fact that all extraneous light is excluded and concentration is actually forced on the user or it may be due to the fact that the user sees no flat piece of paper but only the thing pictured. Whatever may be the reason for the effect, it is a fact that the impression of depth and reality is present and the picture appears to be truly stereoscopic.

In view of the foregoing it will be understood that the words "printed matter" in the appended claims are not to be limited to printed matter of a typographic character adapted to be read but also include photographs or pictures arranged in the form of panels and which may be merely observed through the lens or glass.

Having now described my invention, what I claim as new therein and desire to secure by Letters Patent is as follows:

1. An improved reading machine, the combination with a vertical main frame and a lens or glass carried thereby, of a paper carrier adjustable vertically with respect to the lens, a paper strip mounted in said carrier and moving horizontally therein, said paper strip being provided with printed matter arranged in the form of panels extending in horizontal rows one above the other and a vertically adjustable handle frictionally engaging the main frame and telescoping with respect thereto.

2. In a reading machine, the combination with a main frame and a lens or glass fixedly supported thereby, of a supporting strip spaced from the rear face of the main frame, a paper carrier mounted on said strip and adjustable vertically thereon, and a paper strip mounted in said carrier and moving horizontally therein, said paper strip being provided with printed matter arranged in the form of

panels extending in horizontal rows one above the other.

3. In a reading machine, the combination with a main frame and a lens or glass fixedly supported thereby, of a supporting strip spaced from the rear face of the main frame, a paper carrier mounted on said strip and adjustable vertically thereon, friction means between the paper carrier and said supporting strip for holding the paper carrier in any position of vertical adjustment, and a paper strip mounted in said carrier and moving horizontally therein, said paper strip being provided with printed matter arranged in the form of panels extending in horizontal rows one above the other.

4. An improved reading machine, the combination with a vertical main frame and a lens or glass fixedly carried thereby of a paper carrier adjustable vertically with respect to the lens, a paper strip mounted in said carrier and moving horizontally therein, said paper strip being provided with printed matter arranged in the form of panels extending in horizontal rows one above the other and a feeding roller adapted to be pressed into contact with the paper strip and to be rotated, whereby the strip will be fed horizontally.

5. An improved reading machine, the combination with a vertical main frame and a lens or glass carried thereby, of a paper carrier adjustable vertically with respect to the lens, a paper strip mounted in said carrier and moving horizontally therein, said paper strip being provided with printed matter arranged in the form of panels extending in horizontal rows one above the other, a shaft carried by the main frame and movable towards and away from the same, a knurled wheel on said shaft for rotating the same, and a feed wheel on said shaft adapted to be pressed into contact with the paper strip and be rotated, whereby the strip may be fed horizontally.
